UNITED STATES PATENT OFFICE.

WILLIAM J. GREENWOOD, OF TARENTUM, PENNSYLVANIA, ASSIGNOR TO
CHARLES L. FLACCUS, OF PITTSBURG, PENNSYLVANIA.

PRESS-MOLD FOR HOLLOW ARTICLES.

SPECIFICATION forming part of Letters Patent No. 696,480, dated April 1, 1902.

Application filed July 12, 1901. Serial No. 68,008. (No model.)

To all whom it may concern:

Be it known that I, WILLIAM J. GREENWOOD, of Tarentum, Allegheny county, Pennsylvania, have invented a new and useful 5 Press-Mold for Hollow Articles, of which the following is a full, clear, and exact description, reference being had to the accompanying drawing, forming part of this specification, in which the figure is a sectional side 10 elevation showing my improved press-mold with the blank in place.

My invention relates to the forming of hollow glass articles formed by pressing and then expanding the pressed blank, and especially 15 to the making of bottles and jars, and is designed to provide an improved press-mold which will do away with the annular seam or recess usually formed on the outer surface of the upper bulb-shaped enlargement of the 20 neck and to prevent the burning out of the upper parts of the mold and afford a simple and effective construction.

In the drawing, 2 represents the body of a press-mold, and 3 a two-part hinged mold-ring which seats upon the top of the press-mold.

4 is a top collar or plate through which the plunger 5 is reciprocated during the pressing operation. This plate is provided with an 30 annular projection 6 around the central hole for the plunger, this projection forming a groove or recess in the mouth of the bottle where this recess is desired. The joint between the plate and the mold-ring extends 35 vertically from the top of the recess forming the enlargement around the mouth of the bottle or jar, as shown at 7. Above this joint the plate is provided with an enlarged portion 8, which fits within a corresponding 40 recess in the mold-ring, the faces of these parts being preferably beveled or inclined to guide them into registering position.

The pressing operation is carried out in the usual manner, and there being no horizontal

joint between the plate and the mold-ring at 45 an intermediate point of the neck a seamless neck is formed. The pressed blank is then expanded in a well-known manner by blowing or otherwise.

The advantages of the invention result from 50 the use of the collar or mold-ring having a curved recess in connection with a top plate forming the vertical joint at the top of the neck and having a portion entering the neck.

Many variations may be made in the form 55 and shape of the mold, the mold-ring, and plate, as well as the shape of the article, without departing from my invention.

I claim—

1. A press-mold for bottles or other hollow 60 articles having a mold-ring centered thereon, a top plate having interfitting projections and recesses with the mold-ring, said plate forming a joint with the mold-ring at the top of the bottle, and having a projection entering 65 the mouth of the bottle, and a central hole in said plate for the passage of the plunger for pressing the bottle; substantially as described.

2. A press-mold for bottles or jars, having 70 a mold-ring centered thereon and provided with a globular recess arranged to form a projection at the upper end of the neck, a top plate having interfitting projections and recesses with the mold-ring, said plate forming a vertical joint with the mold-ring at the 75 top of the bottle and having a projection entering the mouth of the bottle, the plate also having a central hole for the passage of the plunger for pressing the bottle; substantially 80 as described.

In testimony whereof I have hereunto set my hand.

WILLIAM J. GREENWOOD.
